TANK BALL

John H. Ross, Jr., 1225 Lydia,
Kansas City, Mo. 64106

Filed Dec. 26, 1967, Ser. No. 9,926

Term of patent 14 years

Int. Cl. D23—01

U.S. Cl. D23—33

Fig. 1.

Fig. 2.

Fig. 3.

Fig. 4.

Fig. 5.

FIG. 1 is a perspective view of a tank ball embodying my design.

FIG. 2 is a side elevational view thereof.

FIG. 3 is a top plan view thereof.

FIG. 4 is a bottom view thereof.

FIG. 5 is a vertical cross sectional view thereof.

The characterizing features of my design reside in the specific configuration from the large central disc portion to the top of the tank ball as shown.

I claim:

The ornamental design for a tank ball, as shown and described.
